WINDOW

Michael J. Hecimovich, Park Falls, Wis.

Application December 31, 1948, Serial No. 68,511

3 Claims. (Cl. 20—53)

1

The invention relates to windows.

The general object of the invention is to provide a window sash construction adapted for mounting in a window frame opening and provided with interchangeable glazed sash and screen sash. More particularly, the invention has for its object a simple and improved form of pivotal mounting for the upper and lower glazed sash sections and the lower screen sash section.

A further object of the invention is to provide an improved sash frame construction.

The invention further consists in the several features hereinafter described and more particularly defined by claims at the conclusion hereof.

In the drawings:

Fig. 1 is a front or outside elevation view of a window embodying the invention;

Fig. 2 is a detailed vertical sectional view taken on the line 2—2 of Fig. 1;

Fig. 3 is a detailed vertical sectional view taken on the line 3—3 of Fig. 1;

Fig. 4 is a back or inside elevation view of the improved window sash;

Fig. 5 is a vertical sectional view taken on the line 5—5 of Fig. 4;

Fig. 6 is a view similar to Fig. 5 showing the sash sections in open position;

Fig. 7 is a detailed horizontal sectional view taken on the line 7—7 of Fig. 6;

Fig. 8 is an inside view of the upper portion of the window sash as equipped with a screen sash;

Fig. 9 is an inside view of the lower portion of the window sash as equipped with a screen sash;

Fig. 10 is a detailed side view of one of the sash locks and limiter.

Referring to the drawings, the numeral 11 designates the permanent window frame in which the frame 12 of my improved sash construction is removably mounted and secured by the buttons 13.

The frame 12 comprises side uprights 14 and an upper cross frame member 15 of wood and a lower cross bar 16 of metal secured to the lower ends of the uprights 14 at the inner sides thereof. This frame has a metal sash support and pivot bar 17 of U-shaped construction whose legs 18 are anchored at their ends 19 to the outside of the uprights 14 intermediate their ends, the transverse portion 20 of said bar being of round cross section.

The opening 21 of the frame 12 is adapted to receive sets of glazed sash or screen sash. As shown in Figs. 1 to 7, a pair of glazed sash 22 are mounted in this frame, each including a frame 23 in which the glass 24 is mounted and secured.

2

The upper of the sashes 22 is provided on its lower front side with spaced bearing brackets 25 adapted to pivotally engage the transverse portion 20 of the bar 17. The lower of the sashes 22 is provided on its upper front side with spaced bearing brackets or rounded hooks 26 adapted to pivotally engage the transverse portion 20 of the bar 17. Thus both sash 22 are hung from or adapted to pivot about a common pivot bar 17. These sash in the closed position abut each other to form a weather tight seal, as shown in Figs. 2 and 3, it being noted that the upper sash has a tongue 27 engaging in a recessed portion 28 of the lower sash and a recessed portion 29 engaged by a tongue 30 on the lower sash. The sides of each sash 22 also have a tongue 31, as shown in Fig. 7, adapted to abut the sides of the sash frame 12 when the sashes are closed to form a weather seal. The top 32 of the upper sash engages the cross frame member 15 of the frame 12 when said sash is closed, and the bottom 33 of the lower sash engages the sill of the frame 11 when the lower sash is closed.

For locking each sash in closed position, the frame 12 carries brackets 34 mounted on the inner side of the uprights 14 and provided with an elongated opening 35 and a slot 36 extending into the medial portion of said opening. Each sash 22 carries bars 37 pivotally mounted thereon at 38 and adapted for insertion in the openings 35 and provided with ringed handle ends 39. Each sash also is provided with hooks or catches 40 adapted to engage the bars 37 when the sash is closed and the bars 37 are turned down to engage with said catches, as shown in Figs. 4 and 5. In the open position of the sash, the bars 37 form stops to limit the extent of opening or swing of the sash about the pivot bar 17, each bar 37 having a notch 41 (see Fig. 10) that engages the side of its bracket 34 when the sash is in an open position. These notches 41 also permit the removal of the bars 37 from the brackets 34 when it is desired to remove the sashes 22 from the frame 12 because they allow the bars 37 to be passed through the slots 36.

Sash similar in construction to the glazed sash 22 but having screen instead of glass may be used interchangeably with the sash 22 above described, but to simplify the construction I prefer to use the screen sash 42 shown in Figs. 8 and 9.

The upper screen sash 42 has a frame 43 of the general form of the glazed sash and adapted to fit within the frame 12 in weathering contact therewith except that it is not mounted on the bar 17 but is secured in position in the frame 12

by buttons 44, as shown in Fig. 8. The lower screen sash 42 is generally similar to the lower sash 22 and has hooks (not shown) similar to the hooks 26 to engage the bar 17, so that this lower section may be swung outwardly, if desired, but instead of using the locking means heretofore described including the bars 37, this sash 43 is held in closed position by the buttons 45. A screen 46 is mounted in each frame 43. The screen sash 42 have the same form of joint between the upper and lower sashes as that described and shown in connection with the glazed sash. The upper screen sash has handles 47 mounted thereon, and the lower screen sash has a handle 48.

With the above construction it will be noted that the bar 17 forms a transverse reinforcing frame member for the sash receiving frame and permits ready mounting of the sash on said frame and that the glazed sash are readily interchangeable with the screen sash. In interchanging the sash it is not necessary to place the sash in the frame 12 from the outside but said sash may be placed in the frame 12 from the inside by inserting them through the frame opening at an angle to clear the brackets 34 and then hooking them onto the bar 17 and swinging them back to a closed position with the bars 37 properly disposed in the openings 35, the pivotal mounting of said bars 37 permitting a limited amount of lateral movement thereof for entry or withdrawal of said bars through the slots 36.

I desire it to be understood that this invention is not to be limited to any particular form or arrangement of parts except in so far as such limitations are included in the appended claims.

What I claim as my invention is:

1. In a window construction, the combination of a sash receiving frame having a single opening therein, a metal cross bar mounted on said frame in a horizontal position and medially of

said opening and forming a window sash support and pivot, a pair of window sash mounted in said opening in abutting relation when closed and having bearing brackets engageable with said bar, and means for holding each sash in either an open or a closed position.

2. In a window construction, the combination of a sash receiving frame having a single opening therein, a U-shaped metal cross bar mounted on the sides of said frame in a horizontal position and medially of said opening and forming a reinforcing frame member, window sash mounted in said opening in abutting relation, and means for locking said sash in said frame, said frame also having a transverse metal frame member at the lower end and on the inner side thereof to reinforce said frame.

3. In a window construction, the combination of a sash receiving frame having side members and a top cross member forming an opening, a U-shaped metal cross bar mounted on the outside of said frame in a horizontal position and medially of said opening and forming a window sash support and pivot, a pair of window sash mounted in said opening in abutting relation when closed and having bearing brackets engageable with said bar, a horizontally disposed metal cross bar at the lower portion of said frame forming a stop for the lower of said sashes, and means for holding each sash in either an open or a closed position.

MICHAEL J. HECIMOVICH.
